ACID RESISTING LINING

Richard Neuhaus, Buffalo, N. Y., assignor to
Nukem Products Corporation, Buffalo, N. Y.

Application August 11, 1941, Serial No. 406,318

5 Claims. (Cl. 72—14)

The present invention relates to acid resisting tanks and more particularly to such tanks provided with an improved brick lining.

Many proposals have been made heretofore of special types of linings for acid resisting tanks, such as pickling tanks, but all have been ignored in preference to tanks lined with rectangular acid resisting bricks bonded with a thermoplastic or thermosetting cement. When a thermoplastic cement is employed to bond the brick it is poured in hot molten condition into the open joints formed after the brick-work has been loosely assembled by spacing each unit brick from other units.

Normal pickling operations are carried out with acid at temperatures between 160—190° F. at which temperature the bond is not adversely affected. However, the present tendency in pickling operations is to operate at much higher temperatures, say 220° F. to the boiling point of the pickling solution. At such elevated temperatures there is a tendency for the bond to deteriorate after long continued use whereby the life of the bond is decreased; this applies to thermoplastic as well as thermosetting bonds.

The present invention provides an acid resisting lining designed to withstand high temperature operations and to permit of the increased output obtainable at the higher temperatures.

The present invention is designed further to avoid the disadvantages inherent in the usual brick lining made of a plurality of layers of brick.

The invention also provides a lining of a plurality of layers or tiers of brick in which the layers or tiers are bonded together with acid resisting cement and are also keyed together mechanically.

In the drawing, wherein like numerals designate like parts:

Fig. 1 is a top plan view of a fragment of a wall of the improved form of acid resisting tank; and

Fig. 2 is an elevation of a fragment of the improved lining showing the plurality of layers or tiers.

Referring more particularly to the drawing, a pickling tank with the improved lining of the present invention comprises an enclosing structure 10 of the desired shape and dimensions which may be made of any suitable material, such as concrete or steel finished with a rubber lining. In the form shown the enclosing structure is of concrete which forms the enclosing and retaining sides and bottom of the tank.

The lining of the tank is built up of an improved form of brick 11 in the form of a T, well

shown in plan in Fig. 1. The brick is provided with a major elongated portion 12 having a tongue 13 located centrally upon one edge thereof. In observing the brick in plan the ends 14 and 15 are parallel to provide close abutment in assembly. However, the edges 16 and 17 of tongue 13 are tapered as shown to provide a mechanical key in assembly of two layers as clearly shown in Fig. 1.

10 A brick that has been found of suitable dimensions is one having a height of 4½ inches, a length of 9 inches and a maximum depth of 5 inches. Of this total depth the tongue portion has a depth of 2½ inches and tapers from a length of 4½ inches to 4 inches. Although these specific dimensions have been found eminently satisfactory, it will, of course, be understood that any other suitable dimensions may be employed, the improved feature of the lining residing in the 15 assembly and bonding of the brick in a completely acid-proof wall, as will be more fully disclosed hereinafter.

The improved lining comprises an inner layer 18 and an outer layer 19, each of the desired 20 number of courses of brick. Inner layer 18 is formed of individual units of brick bonded to each other and to the enclosing structure 10 in all joints except those formed between vertical edges 14 and 15 which closely abut. Outer layer 25 19 is bonded to inner layer 18, the individual bricks of layer 19 having no bond along their adjacent vertical edges or horizontal faces.

In laying up the lining wall, the flat edge 21 of the acid resisting brick is placed adjacent to but 30 spaced from the concrete enclosing structure 10 with its major axis parallel to the wall and with the side edges 14 and 15 in contact. Additional courses of brick of inner layer are built up first by placing such courses on spacers or shims to 35 provide an open horizontal joint. The outer layer is then laid up and keyed to the inner layer as shown. The bricks in layer 19 are not spaced apart horizontally and vertically but are laid adjacent one another, the only joint being the 40 zig-zag joint 22 between layer 18 and layer 19. The acid resisting thermoplastic bond is then 45 poured in molten condition into the open joints and finds its way into the joints and between the individual unit bricks of layer 18, there solidifying to cement the individual units of layer 18 together. At the same time inner layer 18 is 50 bonded to the enclosing structure 10 and to outer layer 19.

In general there is no coincidence between the 55 horizontal joints of the inner and outer layer due

to the fact that the outer layer is laid up with bare brick without spacing the brick vertically and without providing a bond in the horizontal joint in the outer layer.

This mode of assembly provides a rigid lining assembly that may be readily and easily assembled and one that is monolithic in construction notwithstanding the absence of cement in the horizontal joints of outer layer 19.

Notwithstanding the fact that the pickling bath may be operated at temperatures above normal, i. e., 160-190° F., the bond in the inner layer 18 is protected by the facing of brick in the outer layer 19 through which a considerable temperature drop occurs. The effective life of the lining is therefore not decreased even though the pickling bath be operated at the boiling point to obtain greater output.

What is claimed is:

1. An acid resisting tank comprising an enclosing structure and a lining of acid resisting brick therefor, said lining comprising an inner tier of individual bricks bonded to each other and to the enclosing structure with acid resisting cement, and an outer tier of loosely laid bricks abutting each other but bonded to the inner tier with acid proof cement.

2. An acid resisting tank comprising an enclosing structure and a lining of acid resisting brick therefor, said lining comprising an inner tier and an outer tier of individual bricks, said inner tier being bonded in the horizontal joints, the inner and outer tiers being bonded together with acid resisting cement, the horizontal joints of the inner and outer layers being in different parallel planes

whereby the cement between the two tiers of bricks is protected from the action of acid at relatively high temperatures.

3. An acid resisting tank comprising an enclosing structure and a lining of acid resisting brick therefor, said lining comprising an inner and outer tier, said inner tier being bonded to the outer tier and to the enclosing structure with acid resisting cement, said tiers being formed of individual units assembled with mechanically co-operating interlocking tongue members whereby the cement between the two tiers of bricks is protected from the action of acid at relatively high temperatures.

4. An acid resisting tank comprising an enclosing structure and a lining therefor of acid resisting brick, said lining comprising an outer tier of loosely laid individual units abutting each other, and an inner tier of individual units bonded together and to the enclosing structure with acid resisting cement, said tiers being interlocked mechanically and being bonded together with acid resisting cement.

5. An acid resisting tank comprising an enclosing structure and a lining therefor of acid resisting brick, said lining comprising an outer tier of loosely laid individual units abutting each other, and an inner tier of individual units bonded together and to the enclosing structure with acid resisting cement, said tiers being interlocked mechanically and being bonded together with acid resisting cement, the horizontal joints of the layers being in different parallel planes.
